SMOKER'S PIPE MOUTHPIECE DEVICE

James H. Shackleton, Newark, N. J.

Application October 12, 1940, Serial No. 360,909

1 Claim. (Cl. 131—229)

This invention relates to smoking devices such as tobacco pipes, cigar and cigarette holders.

The object of this invention is to provide simple improved means that can readily be applied to existing pipes without requiring any change in the structure thereof, to prevent the direct or concentrated draft of the smoke into the smoker's mouth, with an accompanying burning or biting which is extremely unpleasant and annoying.

The primary object of this invention is the provision of a device of the above mentioned character set forth, that is simple in construction and inexpensive to manufacture, and extremely efficient in use and service.

In describing the invention in detail, reference will be had to the accompanying drawing, wherein like characters denote like and corresponding parts throughout the several views and in which:

Fig. 1 is a perspective view of a pipe in which the invention is applied,

Fig. 2 is a fragmentary enlarged vertical sectional view taken longitudinally through the mouthpiece,

Fig. 3 is an enlarged end elevational view of the same,

Fig. 4 is an enlarged side elevational view of the device,

Fig. 5 is an enlarged perspective view of another form of the device, and

Fig. 6 is a fragmentary enlarged vertical sectional view of another form of the device, taken longitudinally through the mouthpiece.

Referring to the drawing, a pipe is shown as comprising a bowl section 1, which bowl section detachably carries a mouthpiece 2 in a manner well known in the art. The mouthpiece 2 is detachably connected at one end to the bowl section 1 and the free end is adapted for insertion in the smoker's mouth. At the free end, the mouthpiece 2 is thinned out in one direction and widened out in the other, as shown at 3. The mouthpiece is formed with a bore or smoke duct 4 which conforms in shape to the exterior shape of the mouthpiece at the free end. Thus, the smoke duct 4 terminates at the free end in an elongated slot or seat such as shown at 5 in Fig. 3, and preferably but not necessarily of slightly oval-funnel shape.

Referring to Figs. 2, 3, and 4, a cap or plug member is therein illustrated and referred to in its entirety by the reference character 6. This cap member has a closed end or bottom 7 to which is joined the side wall structure 8. This

side wall structure practically conforms in shape to the interior of the flattened out oval shape of the mouthpiece at 9, and is designed to loosely and removably fit therein in the manner shown in Figs. 2 and 3. Secured to the cap member 6 at 10 in any desired or convenient manner is a tube 11, one end thereof extending within close proximity to the closed end or bottom 7 of the cap member, while the other end of the tube 10 extends outwardly sufficiently to be conveniently inserted and frictionally held in the bore or smoke duct 4 of the mouthpiece 2, to prevent accidental separation of the cap member 6 from the bore or duct 4.

15 One portion of the cap member is provided with a plurality of perforations 12 and the opposite portion is provided with a plurality of inwardly extending depressed portions or channels 13. The sidewall structure 8, the seat 9 and external portions of the tube 11 constitute a secondary circumferential chamber around the apex portion of the plug 6. The plug 6 forms the primary chamber for reception of smoke from the bore 4, discharging into the secondary chamber through perforations 12. The channels 13 are widened at the outlet ends relative to the inlet ends thereof to restrict the passage of smoke discharged from the secondary chamber and to retard and hinder any flow of saliva or similar oral liquid matter into the interior passages of the mouthpiece. It is obvious that the cap thus acts as a restriction to the smoke duct which prevents the establishment of a free or open draft.

35 This construction enables the smoke when drawn through the bore or duct 4 to enter the tube 11, and pass into the side wall structure 8 of the cap 6, but due to the closed end 7 is caused to pass through the perforations 12 into the mouthpiece at 9 and from there is then permitted 40 to pass out around the side wall structure 8 into the mouth of the smoker through the depressed portions or channels 13.

In the simplified form illustrated in Fig. 5, most of the material of the portion of the cap 6 containing the perforations 12 is cut away with the exception of the downwardly extending elements 14 which provide means for securing the cap 6 to the tube 11.

50 In the simplified form illustrated in Fig. 6, the tube 11 has been entirely dispensed with and the downwardly extending elements 14 of the cap 6 are of sufficient length to enter the bore or smoke duct 4 of the stem 2 to frictionally and removably hold the cap 6 therein.

55 In the simplified structures illustrated in Figs.

5 and 6, the smoke passes through the bore or duct 4 to the mouthpiece at 9, but due to the closed end 7 is compelled to pass into the smoker's mouth through the depressed portions or channels 13.

It will thus be seen that I have provided a structure adapted to prevent the direct or concentrated draft of the smoke into the smoker's mouth with an accompanying burning or biting which is extremely unpleasant and annoying, and which also provides means for effectually preventing the passage of saliva and moisture from the smoker's mouth into the duct or bore, where it might promote the formation of disagreeable substances.

The structure is simple in construction and inexpensive to manufacture from suitable material, preferably light metal, by the use of ordinary punches and dies.

The foregoing disclosure is to be regarded as descriptive and illustrative only and not as restrictive or limitative of the invention of which obviously embodiments may be constructed including many modifications, without departing from the spirit and scope herein set forth and denoted in the appended claim.

Having thus described my invention, what I claim as new and desire to secure by Letters Patent, is:

5 In a mouthpiece for a smoking utensil having a central bore terminating in a flared seat at the outer end thereof, the combination with said mouthpiece of a hollow coniform plug arranged in said seat and communicating with said bore to primarily receive smoke therefrom, said plug being in substantial engagement with said seat in the base portion thereof and radially spaced therefrom in the apex portion thereof to form a circumferential secondary smoke chamber around said apex portion and having side apertures in said apex portion to communicate with said secondary chamber, an intake tube connected at one end to said plug in the apex thereof and extending inwardly thereinto beyond said side apertures and connected at the opposite end to said bore, said plug having a plurality of circumferentially spaced exterior longitudinal channels depressed in the base portion thereof and communicating with said secondary chamber to discharge smoke therefrom, said channels having the inlet ends thereof restricted relative to the outlet ends to form restrictive passages to smoke discharged therethrough and to saliva entering said channels.
